CLAIM

The ornamental design for a console with illumination, as shown and described.

DESCRIPTION

FIG. 1 is a top front perspective view of a console with illumination showing our new design in a non-illuminated state;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top front perspective view of the console with illumination of FIGS. 1-8 showing an illuminated state;

FIG. 10 is a bottom front perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines in the drawings depict portions of the console with illumination that form no part of the claimed design. The gray oblong features and the text, in FIGS. 1-3, 7 and 8, show the claimed design in an unilluminated state and the black oblong features and the text, in FIGS. 9-11, 15 and 16, show the claimed design in an illuminated state.
